[57] CLAIM

The ornamental design for a cleated sole, as shown and
described.

DESCRIPTION

FIG. 1 is a bottom perspective view of a cleated sole
showing our new design, the contrasting shading on the
cleats being indicative of contrasting color;

FIG. 2 is a lateral elevational view of our cleated sole
design;

FIG. 3 is a front elevational view of our cleated sole
design;

FIG. 4 is a rear elevational view of our cleated sole
design;

FIG. 5 is a medial elevational view of our cleated sole
design;

FIG. 6 is a bottom plan view of our cleated sole design;
and

FIG. 7 is a bottom perspective view of a cleated sole
showing a second embodiment of our new design with
an otherwise smooth sole surface.

The broken line showing of an athletic upper is for
illustrative purposes only and forms no part of the
claimed design.
